UNITED STATES PATENT OFFICE

EMILE MAERTENS, OF PHILADELPHIA, PENNSYLVANIA, ASSIGNOR TO
EMILE SCHEPPERS AND EDWARD SCHEPPERS, OF SAME PLACE.

DESIGN FOR WOVEN FABRIC.

Specification forming part of Design No. **11,538**, dated December 2, 1879; application filed November 10, 1879.
[Term of patent 3½ years.]

To all whom it may concern:

Be it known that I, EMILE MAERTENS, of Philadelphia, Pennsylvania, have produced or invented a new and original Design for a Woven Fabric, of which the following is a specification.

My design is fully shown in the accompanying drawing, which represents an exaggerated view of a piece of the fabric.

The design is of an open or lace-like character throughout, comprising parallel rows of small checks or squares, the rows of squares and the squares of each row being separated by single lines of warp and weft. Each row comprises alternating squares *a* and *b*, the arrangement of the warps and wefts in the squares *a* differing somewhat from their arrangement in the squares *b*. This arrangement, however, while preferred, is not important, as all of the squares

may present the same appearance, or rows of squares of one character may alternate with rows of squares of the other character, without affecting the distinctive features of the design.

Irrespective of the colors employed, I claim—

The design for a woven fabric, said design comprising parallel rows of small checks or squares, separated from each other, so as to give the fabric an open or lace-like appearance, all substantially as shown and described.

In testimony whereof I have signed my name to this specification in the presence of two subscribing witnesses.

EMILE MAERTENS.
